UNITED STATES PATENT OFFICE.

ARTHUR L. MOORE, OF SPRINGFIELD, MASSACHUSETTS.

BOLT-CLIPPER.

No. 806,480.

Specification of Letters Patent.

Patented Dec. 5, 1905.

Application filed April 24, 1905. Serial No. 257,233.

To all whom it may concern:

Be it known that I, ARTHUR L. MOORE, a citizen of the United States of America, and a resident of Springfield, in the county of Hampden and State of Massachusetts, have invented 5 certain new and useful Improvements in Bolt-Clippers, of which the following is a full, clear, and exact description.

This invention relates to improvements in bolt-clippers of the well-known class which comprises compound levers, one pair thereof being handle-levers and the other pair the cutter or die carrying levers; and the invention particularly relates to bolt-clippers of the general class indicated, which includes adjusting-levers jointed to the cutter-carrying levers and means for positioning the adjusting-levers to compensate for the wear or grinding away of the cutters.

25 The object of this invention is to provide a specific, new, efficient, and desirable construction of the adjusting-levers and the combination therewith of the handle-levers, the means for confining the parts in their adjustable relations, and also means for affecting movements of the parts for most conveniently effecting the adjustments; and to these ends the invention consists in the particular constructions and combinations or arrangements of 30 parts, all substantially as hereinafter fully described, and set forth in the claims.

In the accompanying drawings, Figure 1 is a side view of the bolt-clipper, the long handles of which and a portion of one of the adjusting-levers being shown as broken out. Fig. 2 is a vertical section taken through the adjusting-lever pivot on line 2 2, Fig. 1. Fig. 3 is an inner or reversed side view of one of the adjusting-levers. Fig. 4 is a perspective 40 view of certain parts of the bolt-clipper comprised in the present invention shown as in separated relations.

Similar characters of reference indicate corresponding parts in all the views.

45 In the drawings the handles A A, which are of considerable length, are shown as broken away quite near their hinged end portions, and the pivot of said hinge is indicated by a. A semicircular sidewise-open recess or depression B is formed in the handles A, near their pivot a, in which fits the semicircular end portion C of the adjusting-lever D. This end portion C of the adjusting-lever has formed therethrough a concentrically-located square hole 50 d, and centrally located in the semicircular de-

pression B is a round hole c, somewhat larger than the square hole d in the lever end C.

A pivot-bolt E has a head e thereon and a round portion c', which is of the same length and diameter, respectively, as the hole c in 60 which it fits. A square portion d' of the bolt is of the same dimension cross-sectional for a close fit as the square hole d in the adjusting-lever, although the length of such square portion of the bolt is slightly less than the thickness of the said lever. A round screw-threaded portion f of the bolt extends beyond the square portion d' thereof for a distance equal to the thickness of a nut f', which is provided for and has a screw engagement therewith. Beyond 70 this round and threaded portion the bolt terminates in a square portion X of somewhat reduced diameter and of sufficient length to receive the engagement of an ordinary wrench.

The inner flat wall H of the depression B in 75 each handle is provided with radial serrations or fine teeth h, as seen in Figs. 1 and 4, and the contacting face of lever end C has similar teeth i, (see Figs. 1, 3, and 4,) whereby on the adjusting of the lever D a slight loosening of the nut f' permits sufficient separation of the adjacent tooth-provided surfaces H and I, permitting a rotational movement of the round portion c' of bolt E in the hole c in handle A, thereby permitting swinging 80 from this center of the adjusting-lever D through the engagement of its square hole d with the square portion d' of bolt E.

The free end portions of the duplicated adjusting-levers D have formed thereon the ear-lugs g g, between which an end portion, reduced in thickness, of the cutting-lever jaws J are jointed by pivots j. The cutting-jaw levers J are held in pivotal relations to each other by the links K and their pivot connections k k to the end that a movement of the adjusting-levers D relatively to the handles A causes a corresponding change in the relation of the cutting-jaws L to the handles, thereby compensating for wear or any grinding away by a quickly-operated take-up thereof. The operation of performing such a take-up or adjustment of parts consists in loosening the nut f', permitting thereby the free swinging of lever D on its bolt-center E, the 95 control of said swinging adjustment being easily acquired by a wrench engagement of the square bolt end X on the completion of the desired adjustment in the above manner, and a tightening of the nut f' on bolt F draws 100 110

together the roughened or toothed surfaces of the handles and adjusting-levers, respectively and thus firmly locks the same against any independent movements.

5 Having thus described my invention, what I claim, and desire to secure by Letters Patent, is—

1. In a bolt-clipper, the combination with the handle-levers, pivotally connected at their forward extremities and provided adjacent the pivotal connection with sidewise-open recesses having circular serrated bases and partially-circular edge walls, and having perforations transversely and concentrically therethrough, 10 of the cutter-provided levers, and the adjusting-levers, jointed thereto, and having partially-circular extremities and serrated faces, fitted in the said recesses and engaging with the serrated inner walls thereof, and a bolt 15 transversely extending through the handle-levers and said adjacent levers, headed at one end, and threaded, and provided with a binding nut, at its other extremity.

2. In a bolt-clipper, the handle-levers, pivotally connected at their forward extremities 20 and provided adjacent to and rearwardly of

the pivotal connection with sidewise-open recesses having circular serrated bases and partially-circular edge walls, and having the round perforations *c* transversely and concentrically therethrough, the cutter-provided levers, and adjusting-levers jointed thereto and having partially-circular extremities and serrated faces, fitted in the recesses and engaging with the serrated inner walls thereof, and 30 also having the squared hole *d* therethrough, and the bolt transversely extending through the handle-levers and said adjacent levers, constructed with the end head, the cylindrical portion *e'*, the squared portion *d'*, the cylindrical portion *f*, of reduced diameter, and constructed for engagement by a rotating implement, and the nut, all arranged and interengaged substantially as described and for the 35 purposes set forth.

Signed by me at Springfield, Massachusetts, in presence of two subscribing witnesses.

ARTHUR L. MOORE.
